UNITED STATES PATENT OFFICE.

RALPH H. DIXON, OF NEWARK, NEW JERSEY.

CENTRIFUGAL PUMP.

1,050,523.

Specification of Letters Patent. Patented Jan. 14, 1913.

Application filed December 20, 1911. Serial No. 666,977.

To all whom it may concern:

Be it known that I, RALPH H. DIXON, a citizen of the United States, residing at Newark, in the county of Essex and State of New Jersey, have invented certain new and useful Improvements in Centrifugal Pumps, and do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in pumping apparatus; and, the present invention has reference, generally, to a novel construction of pump of the centrifugal type, with a view of providing a 20 simply constructed and efficiently operating centrifugal pump in which the revolutions of the impeller create a vacuum, sucking the water with greater force into the casing of the apparatus, and in consequence discharging the water in greater quantities and greater force than is the case with the usual forms of centrifugal pumping apparatus.

The present invention has for its principal object to provide a centrifugal pump of a 30 simple and unique construction, the general design of which is such that a maximum efficiency is the result.

The invention has for its further object to provide a centrifugal pump, the impeller of 35 which is formed with two sets of vanes of different shapes or configuration, and for the sake of designation will be termed herein as the "power-water-vanes" and the "vacuum vanes", said vanes being alternately disposed thereby producing an apparatus in 40 which the "power-water-vanes" throw the water when received through the suction head; but, the "vacuum vanes" not merely throw the water, but by their revolutions 45 and on account of their shape create a vacuum, and suck in the water with greater force, and on account of the tremendous suction gained discharge the water in great 50 quantities and with increased power from the pump.

The invention has for its further object, by the production of a centrifugal pump provided with the form of "vacuum vanes" herein-above stated, to provide a pump in 55 which the usual vacuum-seals formed in the suction passages are broken, thereby enabling

the apparatus to pump the water, mixed with air to at least 35 per cent.; and, finally providing a centrifugal pump of maximum efficiency, which is smaller in size and light 60 in weight, and consumes less power in running it, than with the usual forms of centrifugal pumps.

The invention has for its further object to construct the vanes in such a manner so as 65 to provide each vane with what is herein termed a "water-brush", formed by the outgoing water at the leaving edge of each vane, such "water brush" contracting and expanding according to the arithmetical 70 spiral of the casing, and by its action sweeping out all sluggish water and any particles of air which may lie dormant therein and thereby providing a free and unobstructed 75 passage of the water after it leaves the impeller through the discharge-chamber of the pump-casing and out from the discharge opening or exit of the same, and at the same time aiding in the creation of the vacuum hereinabove mentioned.

80 Other objects of this invention not at this time more particularly enumerated will be clearly understood from the following detailed description of the present invention.

The invention is clearly illustrated in the 85 accompanying drawings, in which:—

Figure 1 is a central longitudinal vertical section of a centrifugal pump, showing one embodiment of the principles of the present invention; and Fig. 2 is a transverse vertical 90 section of the same, said section being taken on line 2—2 in said Fig. 1, looking in the direction of the arrow α .

Similar characters of reference are employed in all of the above described views, 95 to indicate corresponding parts.

Referring now to the said figures of the drawings, the reference-character 1 indicates one form of centrifugal pump made according to and embodying the principles of 100 the present invention, the same comprising a main member or element 2 which is of a circular marginal configuration, and is preferably provided with a pair of annular offsets, as 3 and 4, substantially as illustrated 105 in Fig. 2 of the drawings. Connected with and preferably forming an integral part of the central and open portion of said main member or element 2 is a tubular inlet-member or duct 5. Suitably mounted upon the 110 annular shoulder formed by the said shoulder 3 is a chambered cover-section or element 6,

which is suitably secured in its position upon one side of the said main member or element 2 by means of screws or bolts, as 7; but it will be clearly evident that any other suitable means may be provided for securing the said parts in their assembled relation. The said cover-section or element is provided with an inwardly extending tubular hub, as 8, which with a suitable stuffing box 9 that may be provided forms a suitable bearing for a shaft or axle 10, the said shaft being provided at its inner end-portion with a collar or annular shoulder, as 11, which is preferably fitted into and runs in a correspondingly formed depression, as 12, with which said tubular hub 8 may be provided. Connected with and forming an integral part of the said cover-section or element 6 is an annular chambered portion or element 13, which is of a substantially circular cross-section, as indicated at 14, and as clearly shown in said Figs. 1 and 2 of the drawings. This chambered element 13 provides a suitable diffusion chamber through which the fluid moves and is finally forced with great pressure or force from a tubular outlet-member or element 16 which is connected with the chamber of said element 13. The said chambered portion or element 13 is also provided with a narrow portion 15 which is concentric with the expelling portion of the impeller disk or element to be presently described, for forcing the fluid from the blades or vanes of the impeller into said diffusion chamber, to be whirled about the said chamber and forced under pressure from the outlet-member or element 16, as will be clearly evident. The said impeller-disk or member consists, essentially, of two disk-like elements or plates 17 and 18 which are of circular marginal configuration, said elements or plates 17 and 18 being placed apart, so as to provide a space between them and having suitably arranged in said space a number of alternately disposed spiral impeller-vanes, as 19, and the vacuum-providing vanes 20, all of said vanes or blades extending laterally across the said space and being preferably integrally connected with the oppositely disposed faces of the said disk-like elements or plates 17 and 18, substantially in the manner illustrated in said Fig. 2 of the drawings. As shown in Fig. 1, the impeller blades or vanes 19 are formed with the convex surfaces 21 for causing an easy and practically frictionless flow of the fluid into the diffusion chamber, and with the convex impact-receiving and power-producing surfaces 22, upon which the energy of the impelling fluid is exerted for producing the rotary and impelling action of the impeller.

The vacuum-providing vanes or blades 20 are formed with a concavo-convex surface, as 23—24, the concave portion 23 serving

also as an impact-receiving and power-producing surface which acts in conjunction with the impact-receiving and power-producing surfaces 22 of the vanes or blades 19, so as to impel the impeller with increased power or force, and the convex surface-portions 24 serving as a means which causes the fluid to leave the vanes or blades 20 with an easy and frictionless flow. The opposite face of the vane or blade 20 is made with a convex-concavo surface, as 25—26, so as to provide a narrow space, at 27, between each pair of vanes or blades 19 and 20, and an increased space 28 between said vanes or blades 19 and 20, to provide a wide discharge-portion from the impeller into the diffusion chamber. At the same time, as will be clearly evident, the fluid, as it leaves the convex surface-portion 25 of the vane or blade 20, rushes past the concave surface-portion 26, so as to extract any air that may be contained in the fluid, and thereby forming a positive vacuum in the pocket-like depression 30 formed by the said concave surface-portion 26. Thus it will be evident, that no air can collect between each pair of blades or vanes 19 and 20, to the detriment of the efficiency of the apparatus; and, with the vacuum created, the fluid is sucked with increased force from between the said vanes or blades and discharged with greatly increased and maximum efficiency into the diffusion chamber and from the discharge-member 16 of the centrifugal pump. The said vanes or blades 19 and 20 are also provided in their outer and leaving edge-portions with a suitably formed means, preferably in the form of depressions or grooves, as 31, over which the fluid as it passes from the revolving impeller forms suitable water-brushes or riffles. These grooves or cuts 31 preferably extend along the entire edge of each vane or blade, from the disk-like element or plate 17 to the disk-like element or plate 18; and, by the revolutions of the impeller the outgoing fluid or water in striking these grooves or cuts 31 will form natural water-brush or riffles which contract and expand according to the arithmetical spiral of the casing, and serve as a means for sweeping out of the diffusion chamber all sluggish water, and any particles of air that may otherwise remain dormant therein. The action of the afore-said grooves 31 is such that as the water leaves the face of each vane, and flows over the grooves, it is whirled into an eddy at each leaving edge of the vane, thus causing the volume of water to expand and contract, with relation to the arithmetical spiral of the casing, and sweeping out of the casing all water which may otherwise remain sluggish or dormant between the vanes. Owing to this fact, it is possible to obtain the maximum benefit of each and every revolution of the impeller to

produce a positive pressure. This action of the fluid or water at the leaving edges of the vanes or blades also aids in the creation of the aforesaid vacuum, while creating an increased and unobstructed flow of the fluid or water under greatly increased efficiency from the discharge-member 16 of the apparatus. As illustrated in Fig. 2 of the drawings, the said disk-like element or plate 17 is provided with a centrally disposed and laterally extending annular flange, as 32, which extends into the offset 4 herein-above mentioned and is rotatably disposed therein, said annular flange 32 providing the tubular inlet or intake of the impeller. The inner surface of said flange 32 is made convex and is of such curvature, so as to offer the least resistance to the flow of the liquid into the space between said elements or plates 17 and 18. The said element or plate 18 carries a tubular hub or boss, as 33, which is made conical, as shown, and extends partway into the opening forming the said inlet or intake, the said cone-shaped hub or boss being of concave configuration and corresponding to the convex surface of the tubular inlet or intake, so as to offer the least resistance to the flow of the fluid from said inlet or intake, and serving at the same time as a proper director for the fluid or water to the vanes or blades 19 and 20. By means of the said hub or boss the impeller is mounted upon the free end-portion of the previously mentioned shaft or axle and directly against the annular collar or shoulder of said shaft or axle to take up any thrust, and to prevent shock and vibration, and heating due to the rapidly running parts. As shown, the said element or plate 18 may also be provided with suitably disposed holes or perforations, as 34, which establish communication between the space formed between the said disk-like elements 17 and 18 and the chambered portion of the main casing in which the impeller revolves, for the perfect lubrication of the various parts, as will be clearly understood.

From the foregoing description of the present invention, it will be clearly evident, that I have devised a simply constructed and smoothly acting centrifugal pump, which will run with greatly increased efficiency and at a minimum expenditure of cost, the parts of the apparatus having also been reduced to a minimum, and being arranged and constructed so as to offer the least resistance or impediment to the flow or passage of the fluid through the pump, and furthermore preventing shock and vibration.

I am aware that some changes may be made in the arrangements and combinations of the various devices and parts, as well as in the details of the construction of the same, without departing from the scope of

the present invention as set forth in the foregoing specification, and as defined in the claims which are appended to the said specification. Hence, I do not limit my present invention to the exact arrangements and combinations of the said devices and parts as described in the said specification, nor do I confine myself to the exact details of the construction of the said parts as illustrated in the accompanying drawings.

I claim:—

1. A centrifugal pump comprising a main member and cover-section formed respectively with an inlet and an outlet, an impeller-element rotatably arranged between said main member and said cover-section, and impeller vanes connected with said impeller-element, every other vane being provided with a pocket-like depression of such shape so that the fluid passing between each pair of vanes will produce a vacuum between said vanes.

2. A centrifugal pump comprising a main member and cover-section formed respectively with an inlet and an outlet, an impeller-element rotatably arranged between said main member and said cover-section, and impeller vanes connected with said impeller-element, one set of vanes being formed on one side with convex surfaces and upon their opposite sides with concave impact-receiving and power-producing surfaces, and another set of said vanes being provided with pocket-like depressions of such shape so that the fluid passing between the vanes will produce a vacuum between the vanes.

3. A centrifugal pump comprising a main member and cover-section formed respectively with an inlet and an outlet, an impeller-element rotatably arranged between said main member and said cover-section, and impeller vanes connected with said impeller-element, one set of vanes being formed on one side with convex surfaces and upon their opposite sides with concave impact-receiving and power-producing surfaces, and another set of said vanes being provided upon one side with concavo-convex surfaces and upon their opposite sides with convex-concavo surfaces, said last-mentioned concavo surface-portions providing pocket-like depressions of such shape so that the fluid passing between the vanes will produce a vacuum between the vanes.

4. A centrifugal pump comprising a main member formed with an inlet, a chambered cover-section, an annular chambered portion forming a diffusion chamber connected with said chambered cover-section, an impeller-element rotatably arranged within said cover-section, said impeller-element comprising disk-like plates, and impeller vanes between said disk-like plates, one set of vanes being formed on one side with convex

surfaces and upon their opposite sides with concave impact-receiving and power-producing surfaces, and another set of said vanes being provided with pocket-like depressions of such shape so that the fluid passing between the vanes will produce a vacuum between the vanes.

5. A centrifugal pump comprising a main member formed with an inlet, a chambered cover-section, an annular chambered portion forming a diffusion chamber connected with said chambered cover-section, an impeller-element rotatably arranged within said cover-section, said impeller-element comprising disk-like plates, and impeller vanes between said disk-plates, one set of vanes being formed on one side with convex surfaces and upon their opposite sides with concave impact-receiving and power-producing surfaces, and another set of said vanes being provided upon one side with concavo-convex surfaces and upon their opposite sides with convex-concavo surfaces, said last-mentioned concavo surface-portions providing pocket-like depressions of such shape so that the fluid passing between the vanes will produce a vacuum between the vanes.

6. A centrifugal pump comprising a main member formed with an inlet, a chambered cover-section, an annular chambered portion forming a diffusion chamber connected with said chambered cover-section, an impeller-element rotatably arranged within said cover-section, said impeller-element comprising disk-like plates, and impeller vanes between said disk-like plates, every other vane being constructed so that the fluid passing between each pair of vanes will produce a vacuum between said vanes, and said vanes being formed in their leaving edges with grooves or cuts adapted to produce water-brushes or riffles of the fluid as the same leaves said vanes.

45. 7. A centrifugal pump comprising a main member formed with an inlet, a chambered cover-section, an annular chambered portion forming a diffusion chamber connected with said chambered cover-section, an impeller-element rotatably arranged within said cover-section, said impeller element comprising disk-like plates, and impeller vanes between said disk-like plates, every other vane being provided with a pocket-like depression of such shape so that the fluid passing between each pair of vanes will produce a vacuum between said vanes, and said vanes being formed in their leaving edges with grooves or cuts adapted to produce water-brushes or riffles of the fluid as the same leaves said vanes.

8. A centrifugal pump comprising a main member formed with an inlet, a chambered cover-section, an annular chambered portion forming a diffusion chamber con-

nected with said chambered cover-section, an impeller-element rotatably arranged within said cover-section, said impeller-element comprising disk-like plates, and impeller vanes between said disk-like plates, one set of vanes being formed on one side with convex surfaces and upon their opposite sides with concave impact-receiving and power-producing surfaces, and another set of said vanes being provided with pocket-like depressions of such shape so that the fluid passing between the vanes will produce a vacuum between the vanes, and said vanes being formed in their leaving edges with grooves or cuts adapted to produce water-brushes or riffles of the fluid as the same leaves said vanes.

9. A centrifugal pump comprising a main member formed with an inlet, a chambered cover-section, an annular chambered portion forming a diffusion chamber connected with said chambered cover-section, an impeller-element rotatably arranged within said cover-section, said impeller-element comprising disk-like plates, and impeller vanes between said disk-plates, one set of vanes being formed on one side with convex surfaces and upon their opposite sides with concave impact-receiving and power-producing surfaces, and another set of said vanes being provided upon one side with concavo-convex surfaces and upon their opposite sides with convex-concavo surfaces, said last-mentioned concavo surface-portions providing pocket-like depressions of such shape so that the fluid passing between the vanes will produce a vacuum between the vanes, and said vanes being formed in their leaving edges with grooves or cuts adapted to produce water-brushes or riffles of the fluid as the same leaves said vanes.

10. A centrifugal pump comprising a main member formed with an inlet, a chambered cover-section, a bearing connected with said cover-section, a shaft rotatably mounted in said bearing, an annular chambered portion forming a diffusion chamber connected with said chambered cover-section, an impeller rotatably arranged within said cover-section, said impeller comprising a pair of disk-like plates being provided with an intake opening and an annular flange surrounding said opening, said flange being rotatably connected with the intake or inlet of said main member, and a tubular hub connected with said other disk-like plate for mounting the impeller upon said shaft, said hub being of a concave conformation and extending into the intake-opening of the other disk-like plate, and impeller vanes between said disk-like plates, one set of vanes being formed on one side with convex surfaces and upon their opposite sides with concave impact-receiving and power-producing surfaces, and another set of said

vanes being provided upon one side with concavo-convex surfaces and upon their opposite sides with convex-concavo surfaces, said last-mentioned concavo surface-portions providing pocket-like depressions of such shape so that the fluid passing between the vanes will produce a vacuum between the vanes.

11. A centrifugal pump comprising a main member formed with an inlet, a chambered cover-section, a bearing connected with said cover-section, a shaft rotatably mounted in said bearing, an annular chambered portion forming a diffusion chamber connected with said chambered cover-section, an impeller rotatably arranged within said cover-section, said impeller comprising a pair of disk-like plates being provided with an intake opening and an annular flange surrounding said opening, said flange being rotatably connected with the intake or inlet of said main member, and a tubular hub connected with said other disk-like plate for mounting the impeller upon said shaft, said hub being of a concave conformation and extending into the intake-opening of the other disk-like plate, and impeller vanes between said disk-like plates, one set of vanes being formed on one side with convex surfaces and upon their opposite sides with concave impact-receiving and power-producing surfaces, and another set of said vanes being provided with pocket-like depressions of such shape so that the fluid passing between the vanes will produce a vacuum between the vanes, and said vanes being formed in their leaving edges with grooves or cuts adapted to produce water-brushes or ripples of the fluid as the same leaves said vanes.

12. A centrifugal pump comprising a main member formed with an inlet, a chambered cover-section, a bearing connected with said cover-section, a shaft rotatably mounted in said bearing, an annular chambered portion forming a diffusion chamber connected with said chambered cover-section, an impeller rotatably arranged within said cover-section, said impeller comprising a pair of disk-like plates being provided with an intake-opening and surrounding said opening, said flange being rotatably connected with the intake or inlet of said main member, and a tubular hub connected with said other disk-like plate for mounting the impeller upon said shaft, said hub being of a concave conformation and extending into the intake-opening of the other disk-like plate, and impeller vanes between said disk-like plates, every other vane being provided with a pocket-like depression of such shape so that the fluid passing between each pair of vanes will produce a vacuum between said vanes, and said vanes being formed in their leaving edges with grooves or cuts adapted to produce water-brushes or ripples of the fluid as the same leaves said vanes.

13. A centrifugal pump comprising a main member formed with an inlet, a chambered cover-section, a bearing connected

with said cover-section, a shaft rotatably mounted in said bearing, an annular chambered portion forming a diffusion chamber connected with said chambered cover-section, an impeller rotatably arranged within said cover-section, said impeller comprising a pair of disk-like plates being provided with an intake opening, and an annular flange surrounding said opening, said flange being rotatably connected with the intake or inlet of said main member, and a tubular hub connected with said other disk-like plate for mounting the impeller upon said shaft, said hub being of a concave conformation and extending into the intake-opening of the other disk-like plate, and impeller vanes between said disk-like plates, one set of vanes being formed on one side with convex surfaces and upon their opposite sides with concave impact-receiving and power-producing surfaces, and another set of said vanes being provided with pocket-like depressions of such shape so that the fluid passing between the vanes will produce a vacuum between the vanes, and said vanes being formed in their leaving edges with grooves or cuts adapted to produce water-brushes or ripples of the fluid as the same leaves said vanes.

14. A centrifugal pump comprising a main member formed with an inlet, a chambered cover-section, a bearing connected with said cover-section, a shaft rotatably mounted in said bearing, an annular chambered portion forming a diffusion chamber connected with said chambered cover-section, an impeller rotatably arranged within said cover-section, said impeller comprising a pair of disk-like plates being provided with an intake opening and an annular flange surrounding said opening, said flange being rotatably connected with the intake or inlet of said main member, and a tubular hub connected with said other disk-like plate for mounting the impeller upon said shaft, said hub being of a concave conformation and extending into the intake-opening of the other disk-like plate, and impeller vanes between said disk-like plates, one set of vanes being formed on one side with convex surfaces and upon their opposite sides with concave impact-receiving and power-producing surfaces, and another set of said vanes being provided upon one side with concavo-convex surfaces and upon their opposite sides with convex-concavo surfaces, said last-mentioned concavo surface-portions providing pocket-like depressions of such shape so that the fluid passing between the vanes will produce a vacuum between the vanes, and said vanes being formed in their leaving edges with grooves or cuts adapted to produce water-brushes or ripples of the fluid as the same leaves said vanes.

6

15. In a centrifugal pump, an impeller-element provided with impeller vanes, and means connected with the leaving edges of said vanes for producing water-brushes or 5 riffles of the impelling fluid as it leaves the vanes.

16. In a centrifugal pump, an impeller-element provided with impeller-vanes, and each vane being provided in its leaving 10 edge with a groove or cut adapted to pro-

duce a water-brush or riffle of the fluid as it leaves the vane, substantially as and for the purposes set forth.

In testimony that I claim the invention set forth above I have hereunto set my hand 15 this 18th day of December, 1911.

RALPH H. DIXON.
